FIG. 1

The undisclosed rear is unornamented.

The dominant features of my design reside in the portions shown in full lines.

I claim:

The ornamental design for a combined product display and order placement cabinet, substantially as shown and described.
